UNITED STATES PATENT OFFICE.

GEORGE H. STEWART, OF LOS ANGELES, CALIFORNIA.

CAN-HEADING MACHINE.

No. 830,189.

Specification of Letters Patent.

Patented Sept. 4, 1906.

Application filed July 28, 1905. Serial No. 271,691.

To all whom it may concern:

Be it known that I, GEORGE H. STEWART, a citizen of the United States, residing at Los Angeles, county of Los Angeles, and State of California, have invented certain new and useful Improvements in Can-Heading Machines, of which the following is a specification.

My invention relates to machines for applying heads to can-bodies; and my object is generally to secure such accurate alinement of the can-bodies and the heads to be held thereon as will render possible the employment of heads of a minimum of flare and of the same or even less interior diameter than the exterior diameter of the can-bodies, thus securing a maximum length of contact between the head and body when united, and consequently a strong frictional hold between these parts.

Other objects and advantages will appear in the following description.

The invention consists in the features and combinations and arrangement of parts hereinafter described, and particularly pointed out in the claims.

In the accompanying drawings, Figure 1 is a longitudinal sectional view through the machine with parts in elevation. Fig. 2 is a detail sectional view of the magnetic means for positioning and holding the parts to be united. Fig. 3 is a detail view of electrical contact means associated with the electromagnet. Fig. 4 is an end elevation of the machine with parts broken away. Figs. 5 and 6 are views similar to Fig. 4 with the positioning and holding jaws in different positions from that of Fig. 4, some parts being omitted and some being shown in dotted lines. Fig. 7 is a detail view of one of the movable jaws with means for adjustably holding the same. Fig. 8 is a front view of the jaw of Fig. 7 with parts in section.

In carrying out my invention I feed the can-bodies and heads automatically to registering and holding means at which a field of force is created, acting to hold the said heads while being brought into proper alinement with the bodies for the heading operation. The bodies are fed continuously by gravity down a chute, with their end portions resting on the ledges or rails 1, while the heads are similarly fed from the tables 2 into grooves 3, down which they roll, on edge, by gravity. The lowermost can-body of the series, together with its pair of heads, rests at first upon the

overhanging lips or rims 4 of headers 5 5*, which by being in constant rotation bring around the mouths or inlet-spaces 6 of said headers into position beneath the said can parts, which immediately drop into the space between the plain faces or disk portions 7 of said headers. The mouths or inlet-openings 6 are provided simply by omitting the overhanging rim or rest 4 for a part of the circumference of the headers. The faces or disks 7, it will be noticed, are perpendicular to the axis of the can parts when in position to receive the heading pressure. In the space between the vertical faces of the headers I create a field of force designed to act on the can-heads, causing them to be drawn against the vertical faces of the headers in position to be accurately registered with the can-body, as will be hereinafter described. The force 75 which I prefer is magnetic, derived, preferably, from electromagnets 9, carried by the headers, with their pole-pieces 9* directed toward the space between the headers into which the can parts enter, so that as soon as the said 80 can parts come into the magnetic field the heads will be drawn against the faces of the headers, or rather against the inserted pieces 10 of said headers, which pieces form continuations of the header-surfaces. The inserted 85 pieces are held to the header by the screws 12. The electromagnets are held by the screws 11.

When the can parts enter between the headers, the electromagnets have been brought by the rotation of the headers in the direction of the arrow, Fig. 4, to near their uppermost positions, as shown in said figure. In this position the can parts have also entered between the fixed and movable jaws 13 14, a pair of which is carried by each header on its inner vertical face 7. In the position of Fig. 4 the jaws are open to receive the can parts, and the heads being now subjected to the action of the magnets are held against the faces of the headers, while the jaws close and accurately register the heads and body for the longitudinal pressure necessary to effect the heading operation.

The energizing of the electromagnets is preferably intermittent, and when so applied it is timed to take place when the can-heads have reached their approximate positions. Supposing this to have taken place in Fig. 4 and the headers rotating in the direction of the arrow, the movable jaw will 110 close in respect to the fixed jaw until the position of Fig. 5 is reached. In this action the

jaws will move the can-heads over the face of the headers until they aline accurately with the can-bodies, all the while said can-heads being subjected to the attractive force of the electromagnets. This force is such as to hold the heads, but not sufficient to offer ob-
 5 jectional resistance to the alining action of the jaws. When the jaws reach the closed position of Fig. 5, the longitudinal heading pressure is applied by moving one header axially in respect to the other. For this pur-
 10 pose a grooved cam 15, fixed on the shaft 16 of one header, is employed, which co-operates with a roller 17, journaled on a pin carried by
 15 a fixed bracket 18, so that said shaft is given longitudinal reciprocatory movement for the heading operation. The continued rotation of the headers in the direction of the arrow, Figs. 5 and 6, brings the registering and holding jaws into the position shown in Fig. 6, at which point they have opened, and the movable header having been retracted mean-
 20 while from the other header the headed can is discharged into a chute 19. This discharging action takes place by gravity; but I prefer to employ discharge-arms 20, one of which is attached to each of the movable jaws to give the can a discharging impulse.

Having described the general movements and actions of the organs operating directly upon the can parts, I will now refer to the mechanism for actuating said organs. The right-hand header 5, Fig. 1, as before de-
 30 scribed, is supported by a shaft 16. This is adapted to rotate in bearings 21 22. The left-hand header 5^a is keyed to a hollow shaft 23, rotating in bearings 24 25, and driven by a pulley 26. Rotary motion is communicated from the left-hand header to
 35 the right-hand header and its shaft and cam 15 through a pin 27, fixed to the said left-hand header and passing through an opening in the face-plate 7 of the right-hand header, so as to allow reciprocation of the latter while rotated constantly by said pin. The movable jaws are carried by a rod 27^x, passing through the hollow shaft 23. This rod is op-
 40 erated to give to the movable jaws their opening and closing movements in respect to the fixed jaws by a crank-arm 28, fixed thereon and pivotally connected to an eccentric strap 29, the eccentric of which, 30, turns on a stud 31, fixed to the disk or face plate 32, which may also be a crank. This member 32
 45 is keyed on the hollow drive-shaft 23. The eccentric has an arm 33, connected rigidly thereto and pivotally connected to a link 34, which in turn is pivoted to a bracket or stand-
 50 ard 35 on the base of the machine. The po-
 55 sitions of the crank, eccentric, arm, and link for the receiving, registering, and discharging positions of the movable jaw are indicated in Fig. 4 and in dotted lines in Figs. 5 and 6, and it will be noticed that the arrangement is
 60 such that the operation of said parts results

from the constant rotary movement of the disk 32 in unison with the headers. This operating mechanism for the movable jaws is located at one end of the machine, leaving the space between the headers free and un-
 70 obstructed, except for the presence of the registering and holding jaws, which are thus exposed to view for inspection and are ren-
 dered readily accessible for repairs or adjust-
 75 ment.

The intermittent energizing of the electromagnets and the timing of the action of said magnets to accord with the movement of the can-heads into proper position is effected as follows: A contact-plate 36 is secured to a fiber strip 37, screwed to a bracket 38, fixed to the standard 21. Current is led to this strip through a conductor 39. The rotary head has a brush or contact plate 40, carried by a pin 41, insulated from the header and passing into the same, from which pin the current is conducted to the coil of the electromagnet by a spring 42. The current is grounded through another pin 43, extending into the shell of the header and through the metallic parts of the machine and its frame. There is a contact device, as above described, for each header. At each revolution of the headers the brushes 40 contact with the plates 36, and the electromagnets are energized at the proper moment to attract and hold the can-heads for the registering action by the jaws.

Referring again to the feeding in of the can-heads, I arrange a pin on the inner face of each header in the path of the can-heads. One of these pins is shown at 44, Figs. 4, 5, and 6. Their function is to arrest the movement of the foremost can-head, and thus hold back the other can-heads in their guides or chutes until the cut-off action takes place by the closing of the jaws onto the can parts which have assumed approximate positions. The pin prevents any can-head other than that being acted on from leaving its chute until the jaws in closing have acted like a feed cut-off. The can-head chutes are made wide enough to allow the heads to move freely without binding, and should the foremost head be allowed to assume its position for heading before the feed-cutting-off action of the jaws begins the heads would be free to move past the said foremost head, owing to the width of the mouth of the chute left completely open by the complete advance of the foremost can-head.

The registering and holding jaws are of special formation to accurately register the can parts, avoid excessive wear, and particularly that which in practice heretofore results from the cutting action of the rough edge of the flange against the surface of the jaw by which it is alined. These jaws are illustrated in detail in Fig. 2, and the movable jaw is shown in Figs. 7 and 8. Each jaw

comprises a bearing-surface 45 for the exterior of the can-head and a bearing surface or rib 46 for the exterior of the can-body near the end thereof. The bearing-surface 46 is of smaller diameter than the bearing-surface 45, and between these two bearing-surfaces a groove 47 is formed. The position of the can parts in relation to these bearing-surfaces and the groove in the jaws is illustrated in Fig. 2, from which it will be seen that the groove 47 receives the slightly-flared edge of the flange of the head, so that the said edge is free from contact with all parts of the jaw. The bearing-surfaces 46 and 45 are relatively located, so that the can-body will be held accurately registered with its outer surface in line with the inner surface of the can-head, so that when the heading pressure is applied the head will be thrust onto the end of the body to closely fit the same. The important advantage of this structure, as above indicated, is that the jaws are relieved from wear which would result from the contact of the rough edge of the flange, which rough edge, it has been found in practice, causes a groove to be worn in the jaw by its abrading action, thus destroying the use of the said jaw as a means for accurately holding the head.

In my invention the entire cylindrical surface 45, which is depended upon to accurately align the head with the body, bears only on that portion of the can-head which is smooth, firm, and true, thus insuring an alignment of the utmost delicacy and an entire absence of distortion in the jaws from wear due to the usually abrading action of the rough edges of the can-head. Each jaw is slightly flared at 48.

While I have described electromagnetic means for creating a field of force at the headers to cause the can-heads to be held thereon, I do not limit myself in this respect, though this forms the best means now known to me for this purpose. One advantage of the electromagnetic means is its susceptibility of instantaneous control.

It will be seen from the above that the can-heads will be held accurately in perpendicular position to the normal axis of the can-bodies by being drawn and held against the vertical faces of the headers. In the heading of cans as heretofore practiced it has been necessary in order to properly feed the can-heads to allow sufficient clearance in the guiding or holding members to permit the heads to reach their proper positions, and this clearance gives rise to serious disadvantages in the registering of the can heads and bodies, for the reason that the can-heads are liable to tip and lie in positions slightly inclined to the axis of the can-body, thus rendering header jams likely to occur when the heading pressure is applied, and, further, by reason of the liability of the can-heads to assume the inclined position referred to it has

been found necessary to make the can-heads larger than necessary to accurately fit the can-bodies, so that notwithstanding the inclined position which the can-heads may assume the bodies will enter therein. By reason of this extra diameter which it is necessary to give the can-heads they fit the bodies loosely and frequently come off therefrom in the subsequent operations.

With my invention the heads can be formed with the interior diameter of their cylindrical flanges of the same and of even less diameter than the exterior of the can-bodies, by reason of the fact that the can-heads can be held accurately perpendicular to the axis of the bodies by being attracted against the faces of the headers, and a maximum length and strength of frictional contact will be secured between the body and the head when the heading action is completed.

It will be understood that where I employ the term "attract" in referring to the action of the force employed to act on the can-head I do so in a generic sense as including attraction *per se* or any equivalent holding action.

The movable jaw which is associated with the movable header is arranged to shift along the said shaft to accord with the movements of the header, and it is held to the said header by a clip 50, Fig. 1. In order to adjust the movable jaw about the shaft 27^x and in relation to the jaw fixed to the header, I employ an arm 51, fixed by a set-screw 52 to the said shaft and having an adjusting-screw 53, headed at 54 and engaging the adjustable jaw, a lock-nut being provided at 55. The head 54 of the adjusting-screw engages a slot 56 in the said adjustable jaw, so that in the movement of this jaw due to the movement of the header 5' axially the screw will not become detached from the adjustable arm. The movable jaw 14 has a groove 14^x to permit it to pass over the pin 44.

I do not limit myself to moving only one of the headers nor in any respect except as set forth in the appended claims.

I claim—

1. A can-heading machine comprising a support for maintaining the head in proper position, movable means for alining the can parts, means for positioning and holding the said can-head on the said support under pressure, said positioning means performing its function independently of the alining means, and means for giving an axial pressure to the parts to unite the body and head, substantially as described.

2. A can-heading machine comprising supporting means adapted to position the head perpendicular to the axis of the can to be headed, means for alining the can head and body for the heading pressure, means for creating a field of force at or adjacent the surface of said supporting means to attract or

press the can-head against said surface, the said force acting on the can-head independently of the alining means, and means for giving an axial pressure to the parts to unite the body and head, substantially as described.

3. A can-heading machine comprising supporting means for maintaining the can-head perpendicular to the axis of the can to be headed, means for creating a field of force adjacent the said support to position and hold the head against said supporting means, and means for registering the can head and body, the said can-head being shifted by the said registering means over the said supporting-surface while held thereagainst by the said force and means for giving an axial pressure to the parts to unite the body to the head, substantially as described.

4. A can-heading machine comprising a supporting-surface for maintaining the can-head perpendicular to the axis of the can to be headed, means for intermittently creating a field of force for positioning and holding the head against the said support, the intermittent application of said force synchronizing with the intermittent arrival of the can-heads at the predetermined position, and means for giving an axial pressure to the parts to unite the body and head, substantially as described.

5. In combination in a machine of the class described, jaws for receiving and alining the can parts, a support for maintaining the can-head perpendicular to the axis of the can to be headed, means for creating a field of force to position the said can-head against the said support, and means for giving an axial pressure to the parts to unite the body and head, substantially as described.

6. In combination in a machine of the class described, a jaw for receiving the can-head, a support for maintaining the can-head perpendicular to the axis of the can-body to be headed, means independent of the jaw for creating a force to position the said head against the said support, said force pervading the space adjacent the said support, means for moving the jaw after the head has been positioned by the said force against the said support, and means for giving an axial pressure to the parts to unite the body and head, substantially as described.

7. In combination in a machine of the class described, supporting means for maintaining the can-head perpendicular to the axis of the can to be headed, a magnet for creating a field of force adjacent the said supporting means to position and hold the can-head thereagainst and means movable over the face of the supporting means for alining the can head and body for the heading pressure, substantially as described.

8. In combination in a machine of the class described, supporting means for maintaining

the can-head perpendicular to the axis of the can to be headed, a magnet for creating a field of force adjacent the said supporting means to position and hold the can-head thereagainst, and means for alining the can head and body for the heading pressure, said alining means shifting the can-head over the supporting-surface while held thereon by the action of the magnet, substantially as described.

9. In a machine of the class described, supporting means for maintaining the can-head in the desired position, an electromagnet for creating a field of force to hold the can-head against said support, means for energizing the said electromagnet intermittently and means for alining the can head and body, substantially as described.

10. In combination, the rotating headers having surfaces against which the can-heads are to be held, means for creating a field of force between said headers to position and hold the can-heads against said surfaces, means for feeding the can parts in between the headers, means for alining the can parts, and means for altering the relation between said headers to unite the can parts, substantially as described.

11. In combination, the rotating headers having surfaces against which the can-heads are to be held, means for creating a field of force between said headers at predetermined intervals to position and hold the can-heads against said surfaces, means for feeding the can parts in between the headers, means for alining the can parts, and means for altering the relation between said headers to unite the can parts, substantially as described.

12. In combination, the rotating headers having surfaces against which the can-heads are to be held, means for creating a field of force between said headers, means for feeding can parts means for alining the can parts consisting of the jaws rotating with the headers and having opening and closing action, and means for altering the relation between said headers to unite the can parts, substantially as described.

13. In combination, the rotating headers having surfaces against which the can-heads are to be held, means for creating a field of force between said headers, means for feeding can parts, means for alining the can parts consisting of the jaws rotating with the headers and having opening and closing action, one of said jaws being fixed to the header and the companion jaw being movable in relation to the fixed jaw, and means for altering the relation between said headers to unite the can parts, substantially as described.

14. In combination, the rotary headers, means for creating a field of force between them to position and hold the can-heads against said headers, means for regulating the feed of the can parts consisting of the

overhanging rim of the headers cut away at one part to leave an inlet, means for alining the can parts, and means for altering the relation between said headers to unite the can parts, substantially as described.

15. In combination, the rotary headers, means for creating a field of force between them to hold the can-heads thereto consisting of the magnets carried by said rotary headers, means for alining the can parts, and means for altering the relation between said headers to unite the can parts, substantially as described.

16. In combination, the rotary headers, means for creating a field of force between them to hold the can-heads thereto consisting of the electromagnets carried by the headers to one side of the axis thereof, means for energizing the magnets and means for alining the can parts, substantially as described.

17. In combination the rotating headers having opening and closing action, a driving connection between said headers, adapted to permit said opening and closing action, means for holding the can-heads under pressure against the faces of the said headers and means for driving the rotary headers, substantially as described.

18. In combination, the rotary headers having opening and closing action, the fixed jaws carried by the rotary headers, movable jaws, means for rotating the headers and a rod carrying the said movable jaws with means for operating the said rod, said means being located outside of the space between the headers.

19. In combination, the rotating headers, the alining-jaws rotating therewith, and means for giving an opening and closing action to the jaws as they revolve, said means being located outside of the space between the headers, substantially as described.

20. In combination the rotating headers, alining-jaws rotating therewith, and means for giving one jaw an opening and closing movement in relation to its companion jaw, said means being connected to revolve with the headers and transmit the said opening and closing action to said movable jaw.

21. In combination the rotary headers, the alining-jaws between them, revolving therewith, a member revolving with the headers, driving connections between the said member and the movable jaw and controlling connections between a part of the frame and the said driving connections for converting the rotary motion of the said member to a relative oscillating motion of the movable jaw, substantially as described.

22. In combination, the rotary headers, a hollow shaft on which one is supported, alining-jaws between the headers, one of said jaws being movable in respect to the other, a rod passing through the hollow shaft and means at the outer end of said rod for rotating the same differentially to secure an opening and closing movement of its jaw in respect to the companion jaw, substantially as described.

23. In combination, the rotary headers, the jaws between them, and means for giving an opening and closing movement to one of the jaws, comprising a member revolving with the headers, an eccentric journaled thereon, a crank driven by the strap of the eccentric, a connection between said crank and the movable jaw, an arm connected with the eccentric and a link connecting the said arm pivotally with a part of the frame, substantially as described.

24. In a can-heading machine, a jaw having a space within which to receive a can-head and having also an annular bearing-surface for the body and an annular bearing-surface of larger diameter for the head, with a groove between said surfaces relatively fixed with respect to said surfaces to receive the rough edge of the head-flange, alone, said groove opening into and extending laterally from the space within the jaw, substantially as described.

25. In combination, the rotating headers, means for creating a force intermittently to hold the can-heads against said headers, the alining-jaws rotating therewith, means for giving an opening and closing action to the jaws as they revolve with the headers, and means for altering the relation between said headers to unite the can parts, substantially as described.

26. In combination in a machine for applying heads to cans a heading member, a movable jaw and a fixed jaw coöperating to hold the head of the can, a rocker-rod, a dog or arm fixed thereon and a connection intermediate said arm and the movable jaw, said connection permitting relative longitudinal movement of the movable jaw axially in relation to the rod and the arm thereon and permitting adjustment of the said movable jaw circumferentially and in respect to the arm fixed thereon for the purpose described substantially as set forth.

In testimony whereof I affix my signature in presence of two witnesses.

GEORGE H. STEWART.
